UNITED STATES PATENT OFFICE.

JACOB D. REED, OF SCHUYLKILL HAVEN, PENNSYLVANIA, AND LEO SCHMIDT, OF NEW YORK, N. Y.

UNDERGARMENT.

1,086,724.

Specification of Letters Patent.

Patented Mar. 3, 1914.

Application filed June 22, 1912. Serial No. 705,321.

To all whom it may concern:

Be it known that we, JACOB D. REED, a citizen of the United States, residing at Schuylkill Haven, in the county of Schuylkill and State of Pennsylvania, and LEO SCHMIDT, a citizen of the United States, residing at the city of New York, borough of Brooklyn, county of Kings, and State of New York, have invented new and useful 5 Improvements in Undergarments, of which the following is a specification.

This invention relates to undergarments for women's use and is especially applicable to union garments comprising undershirt, 15 drawers, and underskirt, although our invention may be applied to a garment comprising drawers and underskirt alone, and has for one of its main objects to provide a single garment of one thickness throughout 20 and closed from neck to legs, having all the advantages of two or more garments usually made separate from each other, at the same time avoiding many of the objectionable features and inconveniences found in wearing two or more garments separately constructed.

Our invention has for its further object to provide a simple, graceful and comfortable fitting undergarment for women's use 30 that will hang gracefully upon the figure and be supported comfortably without binding on any portion of the body, and without the use of seams at objectionable points, the special construction and configuration of the garment adapting the same to thoroughly cover the body with comfort and ease to the wearer and to protect the body where most needed, at the same time providing a closed crotch having 35 the necessary elasticity, and leg openings of the necessary fullness of material to permit the lower end of the garment to be drawn to one side when desired.

Other objects relating to our invention 45 are hereinafter stated. Those objects we accomplish by the means herein specified and illustrated in the accompanying drawings in which similar characters of reference indicate similar parts throughout the 50 several views, and in which—

Figure 1 is a rear elevation of a garment embodying our invention, Fig. 2 is a front elevation of the garment shown in Fig. 1, Fig. 3 is a plan of the back section of the 55 garment, Fig. 4 is a front perspective of the

garment applied as when in use, and Fig. 5 is a rear perspective of the garment arranged as shown in Fig. 4.

The garment is preferably made out of tubular fabric of knitted material such as 60 is commonly employed in the manufacture of underwear; the garment, however, if desired, may be made of sheet fabric.

As illustrated in the drawings the front of the garment is preferably made in one 65 section or piece of material forming both the upper or shirt portion 1 and the lower combined underskirt and drawers portion 2. The edges of the front section are cut on lines 4—5 to form the leg portions of the 70 garment especially large and a V-shaped notch is cut in the central portion of the lower end of the front section along the lines 6—7. The back of the garment as illustrated in the drawings comprises an upper or shirt section 8 having shoulder pieces 9 connected with the front sections of the garment, and lower outer sections 11 stitched at their upper edges to the upper section 8 along the line 12. The lateral 80 edges of the upper section 8 are stitched to the lateral edges of the upper or body portion of the front section 1 of the garment along the lines 3—4 of the front section. A central back section 10 is preferably arranged between the two outer sections 11, the outer edges of the sections 11 along the 85 lines 13—14 coinciding with the outer margins of the lower portion of the front section of the garment along the lines 4—5 and 90 being stitched thereto.

The inner edges 15 of the outer sections 11 of the back of the garment are stitched to the outer edges of the middle back section 10 along the lines 16—17. The back 95 section 10 is cut away centrally at its lower portion along the lines 18—19 to form leg pieces, and along the lines 7—19 to form a flap or tongue between said leg pieces. The leg pieces of the back section 10 extend to 100 the ends of the legs of the front section and are stitched at their inner edges to the inner edge of the legs of the front section along the lines 6—19 of said front section. The flap or tongue 20 of the back section 10 is 105 turned forward and stitched at both of its edges to the edges of the cut away portion of the front section along the lines 7—19 of the front section to form a closed crotch.

If desired, the lower portion of the gar- 110

ment may be made without the upper or shirt portion, and a waist band or yoke may be attached to the upper portion of such a garment along the line 12.

5 What we claim as new and desire to secure by Letters Patent is:—

A union garment comprising body and leg portions, said garment being completely closed from the neck portion to the lower 10 ends of the leg portions at both front and rear, a substantially triangular shaped gusset inserted in the rear of the garment extending from the waist line to the bottom of the legs, the intermediate portion of the

lower edge of the gusset being shaped to 15 provide a triangular extension which is stitched to the garment through the crotch and extends to a point above the crotch at the front of the garment.

In testimony whereof we have hereunto 20 signed our names in the presence of two attesting witnesses.

JACOB D. REED.
LEO SCHMIDT.
